(57) **CLAIM**

The ornamental design for a food preparation device, as shown and described.

DESCRIPTION

FIG. 1 is a perspective view of a food preparation device, showing my new design in a first embodiment;

FIG. 2 is a front view of the embodiment shown in FIG. 1;

FIG. 3 is a rear view of the embodiment shown in FIG. 1;

FIG. 4 is a side view of the embodiment shown in FIG. 1;

FIG. 5 is another side view of the embodiment shown in FIG. 1;

FIG. 6 is a top view of the embodiment shown in FIG. 1; and,

FIG. 7 is a bottom view of the embodiment shown in FIG. 1.

The broken lines in the drawings are for environmental purposes only and form no part of the claimed design.
